UNITED STATES PATENT OFFICE.

FRANZ CHRISTOPH BORMANN, OF HAMBURG, GERMANY.

STOVE OR OTHER FURNACE.

SPECIFICATION forming part of Letters Patent No. 594,774, dated November 30, 1897.

Application filed August 1, 1896. Serial No. 601,360. (No model.)

To all whom it may concern:

Be it known that I, FRANZ CHRISTOPH BORMANN, stove-manufacturer, of No. 19 Steinwiete, Hamburg, in the German Empire, have 5 invented Improvements in Stoves or other Furnaces, of which the following is a specification, reference being had therein to the accompanying drawings.

The invention relates to stoves and other 10 furnaces, and has for its object the complete combustion of all gases. For this purpose all the gases developed during combustion are passed again through the furnace, while fresh air is added to them before their escape into 15 the chimney, whereby complete combustion of all particles is obtained and a saving of fuel is effected.

In order that my invention may be better understood, I now proceed to describe the 20 same, reference being had to the accompanying drawings, and to the letters and figures marked thereon.

Figure 1 shows a longitudinal section of a heating-stove. Fig. 2 shows also a longitudinal section of the same, but at an angle of 25 ninety degrees to the former section. Fig. 3 shows a horizontal section through the same stove. Fig. 4 shows a modified construction.

The fire-grate A is surrounded by the two 30 annular shells B and C, which have alternating longitudinal ribs b c, which overlie one another and serve as conductors of heat. The channels formed by the shells B and C have exits at their upper ends into the space H for 35 the completely-spent gases of combustion. Above the fire-grate A and concentrically with the shells B and C are formed two other annular channels D and E for the partially-burned gases and the completely-burned 40 gases. The inner one of these two channels E reaches nearly to the top of the stove and has at its upper end admission-orifices y for the downward passage of the partially-burned gases. The innermost shell forming the wall 45 of this channel extends to the fire. The second concentric shell, which forms the channel D, extends to nearly the bottom of the furnace and has at its lower end orifices 1 2 3 4 5 for the admission to the fire of the fresh air contain- 50 ing oxygen, which enters the stove through suitable air-admission pipes F. Below the air-admission orifices are provided exit-ori-

fices for the completely-burned gases, which end in the space between the shells B and C.

The operation of such a stove is as follows: 55 The gases containing unconsumed particles ascend upward in the innermost shell and enter through the orifices near the top into the innermost annular channel E, in which they descend. The gases then pass again 60 through the heat of the fire, mixing with the fresh air containing oxygen, which is admitted from the outside atmosphere through the orifices in d, and are thus completely burned. The heating-gases formed thereby 65 pass through the smoke-exit orifices provided below the air-admission orifices into the outermost annular channel H, which is provided with the overlapping longitudinal ribs. The latter, which become partly red-hot, burn 70 completely any unconsumed combustible particles which may still be present, and the gases escape now through the exit-channel H and the exit-flue I. The air-admission orifices x made below the annular channel formed by 75 the shells B and C allow fresh air to enter also into this space to facilitate complete combustion.

Another mode of construction of this furnace is illustrated by the vertical section 80 shown in Fig. 4. In this construction the two inner concentric channels D E do not extend to the top, but are considerably shortened. The channel E extends above the fuel and the channel D only above the burning fuel. 85 A partition d² is provided in the channel D and has orifices d³. This partition is arranged directly below the air-admission orifices F. The fresh air which enters through the orifice F can therefore enter only into the fuel through 90 the orifices 1 2 3 of the channel D, and causes the complete combustion of the gases entering through the channel E. The completely-spent gases of combustion pass now while mixing with the air entering at d³ through 95 the holes 4 5 6 7 into the chimney-flue, thence through the chimney into the open air. The other arrangements are the same as previously described with reference to Figs. 1, 2, and 3.

What I claim, and desire to secure by Letters Patent of the United States, is—

The combination, with the grate, of an inner shell, a second shell forming with the first the passage E leading to the fuel-space, com-

municating at its upper end with the interior of the inner shell, and having near its lower end air-passages to the fuel-space, third and fourth shells C, B, having ribs *c*, *b*, forming a final combustion-chamber, communicating at its lower end with the lower part of the fuel-space, means for supplying fresh air to the space without the second shell, and air-

orifices for supplying fresh air to said final combustion-chamber.

In witness whereof I have hereunto set my hand in presence of two witnesses.

FRANZ CHRISTOPH BORMANN.
